(57) **CLAIM**

The ornamental design for a decorative rocker switch, as shown and described.

DESCRIPTION

FIG. 1 is a perspective view of a decorative rocker switch having a horizontally expanded window panel showing my new design;

FIG. 2 is a front view of the decorative rocker switch of FIG. 1;

FIG. 3 is a rear view of the decorative rocker switch of FIG. 1;

FIG. 4 is a side view of the decorative rocker switch of FIG. 1, the other side view being the same;

FIG. 5 is a top end view of the decorative rocker switch of FIG. 1, the bottom end view being the same;

FIG. 6 is a perspective view of the decorative rocker switch of FIG. 1 showing an intended environment in phantom;

FIG. 7 is a perspective view of the decorative rocker switch having a horizontally expanded window panel showing a second embodiment;

FIG. 8 is a front view of the decorative rocker switch of FIG. 7;

FIG. 9 is a rear view of the decorative rocker switch of FIG. 7;

FIG. 10 is a side view of the decorative rocker switch of FIG. 7, the other side view being the same;

FIG. 11 is a top end view of the decorative rocker switch of FIG. 7, the bottom end view being the same; and,

FIG. 12 is a perspective view of the decorative rocker switch of FIG. 7 showing an intended environment in phantom.

The broken lines in the drawing are for illustrative purposes only and form no part of the claimed design.
